(57) **CLAIM**

The ornamental design for an arm protector as shown and described.

DESCRIPTION

FIG. 1 is a front, left, top perspective view of an arm protector of our new design.

FIG. 2 is a front planar view thereof.

FIG. 3 is a rear planar view thereof.

FIG. 4 is a right planar view thereof.

FIG. 5 is a left planar view thereof.

FIG. 6 is a top planar view thereof; and,

FIG. 7 is a bottom planar view thereof.

The broken lines in the drawings are included for the purpose of illustrating unclaimed features and form no part of the claimed design.

1 Claim, 5 Drawing Sheets
